UNITED STATES PATENT OFFICE.

CARL E. ERICSON AND JOHN MARVIN ERICSON, OF EL CAMPO, TEXAS.

TYPE CLEANER FOR TYPEWRITING MACHINES.

Application filed August 1, 1922. Serial No. 578,963.

To all whom it may concern:

Be it known that CARL E. ERICSON and JOHN MARVIN ERICSON, citizens of the United States of America, residing at El 5 Campo, in the county of Wharton and State of Texas, have invented new and useful Improvements in Type Cleaners for Typewriting Machines, of which the following is a specification.

10 The object of the invention is to provide a simple and efficient means for maintaining the type faces of a typewriting machine in proper condition free from accumulations of lint, dust and other foreign substances 15 in the operation thereof without resorting to the operation of specifically cleaning the same as in the ordinary practice; and with this object in view the invention consists in a construction and combination of parts of 20 which a preferred embodiment is shown in the accompanying drawings, wherein:—

Figure 1 is a plan view, and

Figure 2 is a vertical sectional view of a 25 type cleaning device embodying the invention applied in the operative position to a typewriting machine the latter being indicated in outline.

Figure 3 is a detail view in perspective of the device constructed as an attachment for 30 application to a machine of the commercial type.

Figure 4 is an enlarged detail side view 35 of the brush head and adjacent portions of the device.

35 The device consists essentially of a brush head 10 of looped form with the opening of the loop directed downwardly and having side arms 11 consisting of twisted strands of wire or the equivalent thereof from which 40 project bristles 12 arranged to invade the throat or open space between the sides of the loop and bridge or span the latter jointly so that type 13 carried by the type bars 14 must pass through the bristles or the space 45 normally occupied by the bristles in approaching and leaving the platen or roller 15 to the end that the accumulation of lint, ink and dust upon the type faces and side surfaces is prevented and the periodical 50 manual cleaning of the type faces is avoided.

In the illustrated embodiment of the invention the looped brush head is carried by a bracket having arms 16 connected by a central arch 17 and provided with terminal 55 fingers 18 which are inwardly directed and have at their extremities the outwardly fac-

ing hooks 19 which engage with the edges of the guard plate 20 of a typewriter of the Royal type and which, therefore, provide for slipping the cleaner into place and removing the same when necessary without resorting to any supplemental fastening devices. It will be obvious that other constructions of supporting brackets may be employed to suit different types of commercial machines but the purpose is to provide such a construction of bracket as will permit applying the device without special means of attachment in the way of screws or the like although in practice it may be found desirable to build the cleaner as a permanent part of the typewriting machine.

In the illustrated embodiment of the device the frame including the brush head 75 and bracket is constructed of a single blank of wire or rod of which the terminals constitute the bracket arms 16 while the intermediate portion constitutes the sides of the loop forming the brush head, with the ends 80 of the twisted strand portions 11 extended to form looped hooks 21 which engage under the cover or guard plate 20 of the typewriting machine to serve as a supplemental 85 means of maintaining the device in proper position and prevent upward displacement thereof by cooperation with the arms 16 which bear on the upper surface of said cover plate 20.

The looped form of the brush heads provides a throat defined by the twisted strands forming the side members of the loop through which the type heads operate, the plane of the throat being substantially perpendicular to the direction of movement of 95 the type heads as they pass therethrough as will be obvious by reference to Figure 2 of the drawing wherein the pivotal point of the type bar is indicated at 14^a.

Having described the invention, what is claimed as new and useful is:—

1. A type cleaning brush for typewriting machines having a brush head provided with bristles arranged in the path of movement of the type heads in their movement 105 between their positions at rest and their printing positions, the brush head being of looped form defining a throat and having the bristles carried by the side members thereof.

2. A type cleaning brush for typewriting machines having a looped brush head 110

and bristles carried by the sides thereof and invading the throat defined thereby, and a supporting bracket having yielding arms provided with terminal hooks.

5 3. A type cleaning brush for typewriting machines having a looped brush head and bristles carried by the sides thereof and invading the throat defined thereby, and a supporting bracket having yielding arms provided with terminal hooks, the sides of the brush head being provided with outwardly directed machine engaging hooks.

10 4. A type cleaning brush for typewriting machines having a looped brush head and bristles carried by the sides thereof and invading the throat defined thereby, and a supporting bracket having yielding arms provided with terminal hooks, the sides of the loop consisting of intertwined strands 20 extended to form terminal looped retaining hooks.

15 5. As an article of manufacture a type cleaning brush for typewriting machines

consisting of a blank of wire folded upon itself between its extremities to form a 25 looped brush head carrying inwardly directed bristles and a bracket having supporting arms represented by the terminals of the blank and extended to form an arch for continuation of the sides of the said 30 loop.

6. As an article of manufacture a type cleaning brush for typewriting machines consisting of a blank of wire folded upon itself between its extremities to form a 35 looped brush head carrying inwardly directed bristles and a bracket having supporting arms represented by the terminals of the blank and extended to form an arch for continuation of the sides of the said loop, 40 the sides of the loop consisting of intertwined strand portions of the blank.

In testimony whereof they affix their signatures.

CARL E. ERICSON.
J. MARVIN ERICSON.
